ROTARY VALVE

Harold E. McCrery, Pittsburgh, Pa., assignor to
 Blaw-Knox Company, Blawnox, Pa., a corpora-
 tion of New Jersey

Application April 2, 1932, Serial No. 602,830

4 Claims. (Cl. 221—130)

This invention relates generally to apparatus for feeding powdered material, and more particularly to a rotary valve for accurately controlling the flow of such material from a bin or storage hopper. Although the valve is adapted for feeding various powdered materials it is described herein particularly as applied to feeding cement from a hopper.

In the accompanying drawings which illustrate a preferred embodiment of my invention,

Figure 1 is a vertical longitudinal section through the valve and a portion of a hopper communicating with the valve;

Figure 2 is a transverse section on a smaller scale taken on the line II—II of Figure 1, showing the valve in open position;

Figure 3 is a view similar to Figure 2 showing the valve in position to deliver material from the interior of the valve;

Figure 4 is a longitudinal section of the rotary valve taken on the line IV—IV of Figure 2;

Figure 5 is an end view of the valve shown in Figure 4; and

Figure 6 is a broken plan view showing a slide valve and assembly for controlling the flow of material from the hopper into the rotary valve.

Referring more particularly to the accompanying drawings, a valve casing 2 is provided with a flange 3 on its upper edge, the flange 3 being secured by bolts 4 to a flange 5 formed on the lower edge of a hopper 6. Interposed between the flanges 3 and 5 is a frame-work in which a slide valve 7 operates, the slide valve being adapted to control the flow of cement from the hopper into the valve casing. The frame for the slide valve 7 comprises an upper plate 8, a lower plate 9 and a spacer plate 10, the frame forming grooves 11 in which the slide operates. One end of the slide is formed in a vertical flange 12 as shown in Figure 2, the flange serving as a handle for operating the slide. Packing material 13 is placed between the plate 8 and the flange 5, and between the plate 9 and the flange 3. The forward end 15 of the slide valve is formed at each side with plow-shaped projections 16 which prevent cement from sticking in the grooves 11. In the normal operation of the apparatus the slide valve 7 is withdrawn and the slot through which it is inserted is plugged up, the flow of cement being controlled in the normal operation of the apparatus entirely by the rotary valve about to be described. It is only when repairs or replacement of the rotary valve is required that the slide valve is used.

Mounted for rotation within the casing 2 is

a hollow rotor 18 of the shape indicated in Figure 4. The rotor is of general cylindrical shape having closed ends 19. The ends are provided with trunnions 20 which fit in trunnion bearings 21 formed on the casing 2. Secured to one of the trunnions 20 is a sprocket wheel 22 which may be rotated by a chain 22-a from any desired means, for causing rotation of the rotor 18.

Parts of the periphery of the rotor are broken away to form openings 23 and 24 through which cement may be fed when the rotor is in the position indicated in Figure 2. As stated above, when feeding cement in the normal operation of the apparatus the slide valve 7 is pulled out from the position indicated in this figure so as to allow cement to be fed from the hopper through the rotary valve. The remaining portion of the periphery of the rotor forms two closure elements 25 and 26, the element 25 being of greater length than the element 26. The element 25 is longer than the inlet opening 27 of the valve casing so that the element will close the opening when rotated clockwise one-quarter of a revolution from the position indicated in Figure 2. The element 26 is longer than the outlet opening 28 of the valve casing so that it will close the outlet opening when the rotor has been rotated one quarter revolution.

In the operation of weighing out a given quantity of cement, the slide valve 7 is withdrawn and the cement flows through the rotor 18 which is then in the position indicated in Figure 2 and is delivered through the outlet opening 28. After the approximate desired weight has been delivered, the rotor 18 is rotated clockwise one-quarter revolution from the position indicated in Figure 2, thereby completely closing the inlet 27 and the outlet 28. The final accurately measured quantity of cement is then supplied from the cement contained within the interior of the rotor 18 by further rotating the rotor until it is in the position indicated in Figure 3. In this position the inlet is closed but the interior of the rotor is in communication with the outlet opening 28 so that small quantities of the cement within the rotor can be delivered without being under the influence of the cement in the hopper. When the desired amount of material has been delivered the rotor is rotated counter-clockwise a few degrees from the position indicated in Figure 3 so as to close both the inlet and outlet openings. When it is desired to weigh out another batch of cement the rotor is rotated counter-clockwise until it assumes the position indicated in Figure 2, in which

position the cement is free to flow through the openings 23 and 24 in the rotor.

- In order that small quantities of cement may be delivered from the interior of the rotor during the final part of the weighing operation, a scraper or paddle 30 is disposed inside of the rotor. The scraper is connected by arms 31 to a shaft 32 which extends through one of the trunnions 20 and has a sprocket wheel 33 secured to its end.
- 10 The trunnions 20 act as bearings for the shaft 32 which is rotatable relative to the trunnions. A chain 34 passes around the sprocket 33 and around a sprocket 35 secured to a shaft 36 which may be rotated by means of a crank 37 as shown in Figure 15. 1. Rotation of the crank causes the scraper 30 to rotate in a counter-clockwise direction so as to force cement within the rotor out through the outlet opening 28.
- The ends 19 of the rotor are provided with 20 scraper blades 40 as shown in Figure 5. These blades contact with the inner surface of the casing 2 and prevent cement from sticking between these parts. The cement loosened by the blades 40 falls into an annular pocket 41 shown in Figure 25 1 from where it is delivered through the casing outlet with the rest of the material passing through the valve. The elements 25 and 26 forming a part of the periphery of the rotor 18 are provided with ribs 42 which prevent cement from 30 sticking between the rotor and the inner cylindrical surface 43 of the valve casing.

In the operation of weighing out a quantity of cement or other material, the approximate amount is weighed out when the rotor is in the 35 position indicated in Figure 2 and the cement which is being delivered is under the influence of the weight of the cement which is in the hopper. However, when the approximate amount of material has been delivered, the valve is rotated so as 40 to cut off the supply of cement from the hopper to the interior of the valve and the final quantity is delivered from the interior of the valve by cracking it slightly. During this latter portion of the weighing operation the cement flowing 45 through the outlet opening 28 is not under the influence of the cement in the hopper and, accordingly, small accurately controlled quantities may be delivered. The scraper 30 further aids in delivering accurate quantities of cement from the 50 interior of the valve. The slide valve 7 is provided for the purpose of cutting off supply of cement from the hopper to the rotary valve when it is necessary to repair the rotary valve.

I have illustrated and described the present

preferred embodiment of my invention. It is to be understood, however, that the invention may be otherwise embodied within the scope of the following claims.

I claim:

1. A rotary valve comprising a valve casing having an inlet and an outlet, a hollow rotor having openings in its periphery which when the rotor is in one position communicate at the same time with said inlet and outlet so as to feed material therethrough, the periphery of said rotor forming closure elements for closing the inlet while the interior of the rotor communicates with the outlet, and a rotatable scraper inside of the rotor, 10

15 2. A rotary valve, comprising a valve casing having an inlet and an outlet, a hollow cylindrical rotor having openings through its periphery which when the rotor is in one position communicate at the same time with said inlet and outlet 20 so as to feed material therethrough, the periphery forming closure elements for the inlet and outlet when the rotor is in one position but when in another position closing the inlet while the interior of the rotor communicates with the outlet, a 25 rotatable scraper inside of the rotor, and means operable from the outside of the rotor for operating the scraper.

3. A rotary valve comprising a valve casing having an inlet and an outlet, a hollow cylindrical rotor with closed ends, trunnions on the ends rotatably mounted in the casing, the periphery of the rotor having openings therein which when the rotor is in one position communicate at the same time with said inlet and outlet so as to feed material therethrough, the periphery forming closure elements for the inlet and outlet of the casing when the rotor is in one position but when in another position closing the inlet while the interior of the rotor communicates with the outlet, 35 40 and a shaft extending through one of the trunnions and rotatable relative thereto, a scraper secured to the shaft, and means outside of the valve for rotating the shaft.

4. In combination, a hopper, a rotary valve 45 having an inlet communicating with the hopper, a slide valve for controlling the flow of material from the hopper, a frame in which the slide valve operates, said frame being secured between the hopper and rotary valve and comprising an upper 50 and a lower plate and a spacer therebetween, said slide valve having plow-shaped ends for scraping material from the grooves formed by the frame.

HAROLD E. McCRARY.
